(57) **CLAIM**

The ornamental design for a hydrogen rich water cup, as shown and described.

DESCRIPTION

FIG. 1 is a front view of a hydrogen rich water cup;
FIG. 2 is a rear view of the hydrogen rich water cup;
FIG. 3 is a left side view of the hydrogen rich water cup;
FIG. 4 is a right side view of the hydrogen rich water cup;
FIG. 5 is a top view of the hydrogen rich water cup;
FIG. 6 is a bottom view of the hydrogen rich water cup;
FIG. 7 is a perspective view of the hydrogen rich water cup;
and,
FIG. 8 is a detailed enlarged view of one part of the bottom view.
